E. MÜLLER

FUR TESTING AND CUTTING DEVICE

Filed Nov. 7, 1927

UNITED STATES PATENT OFFICE.

ERNST MÜLLER, OF BERLIN, GERMANY.

FUR TESTING AND CUTTING DEVICE.

Application filed November 7, 1927. Serial No. 231,583.

This invention relates to a fur testing and cutting device of the kind comprising a fur support which is adapted to be depressed together with the fur over a knife whereby the fur is pierced, the fur being exposed to an air blast which is directed towards the knife point and which parts the hair so as to reveal the bald or otherwise defective patches which are to be cut. 5 It has been found in practice that the distance of the air nozzle from the fur requires regulation in order to effect a proper parting of the hairs of different kinds of furs. It has also been found advantageous 10 to maintain the nozzle in an inclined position so that hairs which are severed from the pelt by the knife will be cleared away from the field of operation, and this inclination will have to be varied together with 15 the vertical adjustment of the nozzle in order to keep the latter directed towards the knife point.

The object of the present invention is to meet these requirements, and the invention 20 consists in the provision of a flexible air tube and in supporting said tube on a U-shaped arm one member of which is held adjustably in a supporting socket for regulating the distance of the nozzle from the 25 fur, the other member being jointed so as to allow the nozzle-carrying end of the tube 30 to be set at the required angle.

Figs. 1 and 2 of the accompanying drawings represent elevations of the device at 35 right angles to each other.

In said drawings *g* is the knife whereby the fur is cut, and *e* is the nozzle which directs the air blast to the knife. According to the invention the air is led to the nozzle through a flexible tube *a* which is 40 supported on a U-shaped arm *b*. One member of the latter carries the nozzle *e* in an inclined position, and it is jointed at *f* so as to allow the inclination to be varied. A wing nut *h* is used for rendering the joint 45 rigid and maintaining the nozzle in adjusted position.

The other member of the arm *b* is held in a supporting socket to which it is normally clamped by two screws *d* and *d'*. 50 The arm can be adjusted in the socket for regulating the distance between the nozzle *e* and the knife *g* according to the nature of the fur. The inclination of the nozzle *e* is regulated at the same time so as to maintain the air blast in its proper direction 55 relative to the knife *g*.

I claim:

In a fur testing and cutting device of the character described, an air nozzle, a flexible pipe connected to said nozzle, a U-shaped arm supporting the pipe and holding the nozzle along one of its members, said latter member being jointed so as to allow the nozzle to be set at different angles, and a socket holding the other member of the arm so as to allow the latter and the nozzle to be vertically adjusted. 65

ERNST MÜLLER.
